VOLTAGE DOUBLER CIRCUIT AND APPARATUS

Ted R. Elstrom, Concordia, Kans.

Application July 21, 1939, Serial No. 285,825

1 Claim. (Cl. 171—97)

This invention relates to an improved voltage doubler circuit and apparatus and seeks, among other objects, to provide means whereby direct current voltages may be effectively raised.

Another object of the invention is to provide a circuit and apparatus of this character which will function for raising voltages without the use of transformers, motor generators or vacuum tubes.

A further object of the invention is to provide a voltage doubler circuit and apparatus employing only a vibrator and two condensers for effecting the voltage raising.

A further object of the invention is to provide a voltage doubler circuit and apparatus which is of simple arrangement and construction and which is adaptable for use in any apparatus where the current demand is small.

Other and incidental objects of the invention not particularly mentioned hereinbefore will become apparent during the course of the following description.

My invention is illustrated in the accompanying drawing, wherein:

Figure 1 is a diagrammatic view of the circuit employed.

Figure 2 is an enlarged detail sectional view of the vibrator employed.

Figure 3 is an enlarged detail side elevation of the vibrator at the opposite side thereof from that shown in Figure 2.

Figure 4 is a top plan view of the vibrator, and

Figure 5 is an enlarged detail transverse sectional view of the vibrator.

Referring now more particularly to the drawing, wherein like numerals of reference will be seen to designate similar parts throughout the views, there will be described first the vibrator which forms the moving part of my invention. The vibrator is illustrated in detail in Figures 2, 3, 4 and 5 of the drawing. Said vibrator includes a base 1 having arms or brackets 2 and 3 which are riveted or otherwise suitably secured to one end of the base. The base 1 is of substantially rectangular shape and is formed of any suitable material. Mounted between the brackets 2 and 3 is a magnet coil 4. Pole pieces 5 and 6 of substantially L shape are carried on the brackets 2 and 3 and are mounted in opposed relation.

Mounted on the base at its opposite end and in parallel relation with the brackets 2 and 3 and the coil 4 is a mounting strip 7. The mounting strip 7 has mounted thereon a reed which is indicated generally at 8. The reed 8 is relatively

wide and extends throughout the major portion of the length of the base 1 thereabove and terminates in spaced relation to the inner extremities of the pole pieces 5 and 6. An armature 9 is suitably secured to the reed 8 at its free end. The armature is of soft ferrous metal and is mounted to swing near the pole pieces 5 and 6 so that, when the coil 4 is energized, in a manner to be described in more detail hereinafter, the reed 8 will be caused to vibrate.

The reed 8, as best seen in Figures 4 and 5, has pairs of contacts mounted thereon. More specifically, contacts 10 and 11 are mounted near one edge of the reed at opposite sides thereof and are connected with each other by a stem or bolt 12. The contacts 10 and 11, however, are insulated from the reed by a bushing 13 and strips of insulating material 14 and 15, at opposite sides of the reed. The reed 8 is provided at its opposite edge, with contacts 16 and 17 which are insulated from the reed by the strips 14 and 15 and a bushing 18. The contacts 16 and 17 are connected to each other by stems or bolts 19. As will be apparent from a glance at Figure 4, the contacts 16 and 17 are horizontally aligned with the contacts 10 and 11 so that, in side elevation, but one pair of contacts appear.

Mounted on the reed 8 medially thereof and beneath the contacts 10, 11, 16 and 17 is a contact 20. The contact 20 is connected electrically to the reed and is fixed thereon by means of an upset head 21 or, in any other suitable manner.

In order to cooperate with the contacts 10, 11, 16 and 17, I provide additional contacts 22, 23, 24 and 25. As best seen in Figure 3, the contacts 22 and 23 are mounted on spring contact members 26 and 27 respectively. The spring contact members are carried on the mounting strip 7 in spaced relation to the reed 8 and are so arranged that the contacts 22 and 23 directly confront the contacts 10 and 16, respectively, so that swinging of the reed toward the contacts 22 and 23 will effect engagement between these contacts and said contacts 10 and 16. The contacts 24 and 25 are mounted, as best seen in Figure 2, on spring contact members 28 and 29. The spring contact members 28 and 29, like the contact members 26 and 27, are of sufficient length to position the contacts 24 and 25 to confront the contacts 11 and 17 so that engagement between contacts 11 and 17 and the contacts 24 and 25 may take place when the reed 8 is caused to vibrate. A relatively short spring contact member 30 is also mounted on the strip 7 and carries a contact 31 which is adapted to cooperate with the contact

20 which is mounted on the reed and electrically connected therewith. The spring contact member 30 is of lighter construction than the other spring contact members and is, therefore, capable of greater swinging movement. Springs 32 are carried on the strip 7. A spring 32 is provided for each of the contact springs 26, 27, 28, 29 and 30 and serves to provide proper resilient response of said spring contact members. It will be seen, by referring particularly to Figure 4, that the reed 8 is biased or sprung slightly toward the spring contact members 26, 28 and 30 so that the contacts 20 and 31 will be normally closed. The contacts 16, 17, 24 and 25, however, will remain normally open.

Reference is now had to Figure 1 of the drawing, wherein the schematic wiring diagram is shown. A pair of in-put terminals are indicated at 33 and 34. The in-put terminal 33 is connected, by a conductor 35, to the contact 25, while the terminal 34 is connected to the contact 24 by a conductor 36. A conductor 37 extends from the conductor 35 and is connected with the contact 22. A conductor 38 connects one terminal of the coil 4 with the conductor 37. The other terminal of the coil 4 is connected by a conductor 39 to the contact 31, which is engageable with the contact 20. A conductor 40 connects the conductor 36 with an out-put terminal 41. Another out-put terminal is indicated at 42 and is connected by a conductor 43 with the contact 23. A condenser 44 is connected, by conductors 45 and 46, across the out-put terminals 42 and 41. A second condenser is indicated at 47. This condenser is, by means of conductors 48 and 49 and flexible leads 50 and 51, connected with the contacts 16, 18, 17 and 11. A conductor 52 is connected with the conductor 40 and the reed 8.

The operation of my improved voltage doubler circuit and apparatus will now be described.

A source of direct current to be raised is connected to the terminals 33 and 34. Inasmuch as the contacts 20 and 31 are normally closed, current will flow from the terminal 33 through the conductor 37, the conductor 38, the magnet coil 4, the conductor 39, through the contacts 31 and 20, through the reed 8, through the conductor 52, and back to the terminal 34, through the conductor 36. The reed 8 will thus be caused to vibrate. As the reed vibrates, the contacts 11 and 17 will intermittently engage the contacts 24 and 25, respectively, with the result that the condenser 47 will be charged by the current in the direct current line. The reed 8, of course, effects vibratory engagement between the contacts 16 and 23 and 10 and 22. When these latter mentioned contacts are engaged, the condenser 47 discharges into the condenser 44 with the result that the condenser 44 will be supplied with the voltage of the charged condenser 47, plus the in-put voltage. A pulsating direct current will be generated and said pulsating direct

current will, of course, be of a considerably higher voltage than the in-put voltage. It should be understood that the condensers 44 and 47 will be of proper working voltage to withstand all the voltage developed by the circuit and the vibrator, since the capacity of these condensers is a factor which will determine the amount of current that can be drawn from the circuit. Also, if necessary, a resistor may be inserted in the circuit when voltages higher than the working voltage of the magnet coil are to be used. Protection of the magnet coil will thus be effected. The resistor could well be placed in the conductor 38, and attention is particularly directed to the fact that the contacts 20 and 31 are normally engageable so that operation of the reed will begin as soon as the in-put voltage is applied. Inasmuch as the contacts 22, 23, 24 and 25 are mounted on the spring contact members 26, 27, 28 and 29, respectively, slight misadjustment of any contact will still allow proper engagement of these contacts and the contacts on the reed simultaneously so that the condenser 47 will be charged and discharged. It is pointed out that the spring contact member 30 will have less resistance to movement due to the fact that this contact member will necessarily have to spring farther than the other contacts.

The invention lends itself particularly for use in doubling or raising the voltage of 110 direct current line so that radios or other apparatus, which will not operate efficiently on 110 volts, may be successfully operated. Suitable filtering means, of course, may be inserted in the out-put for this purpose as and if needed.

Having thus described the invention, what is claimed as new is:

In a voltage doubler circuit and apparatus, a 40 vibrator having a pair of arms and a magnet coil, a reed for the vibrator and having a contact mounted on the reed and electrically connected therewith, a second contact, a spring contact member mounting said second-mentioned contact for engagement with the first-mentioned contact, circuit connections between the contacts, the coil and the source of direct current voltage, said coil effecting vibratory movement of the reed, sets of contacts carried by the reed and insulated therefrom, a condenser connected 45 across the sets of contacts, cooperating contacts, means mounting said cooperating contacts for vibratory engagement with the sets of contacts on the reed, a pair of output terminals, a second condenser, and circuit connections between the sets of contacts, the condensers and the output terminals, said sets of contacts and reed cooperating for charging the condenser from the in-put voltage whereby the condenser will add to 50 said input voltage for raising the voltage at the output terminals upon discharge of certain of said condensers.

TED R. ELSTROM.
